SCRUBBER FOR REMOVING DIRT FROM AGGREGATES SUCH AS SAND AND GRAVEL

George Ernest Moyer, Alturas, Calif.

Application August 24, 1945, Serial No. 612,495

7 Claims. (Cl. 209—452)

1

The present invention relates to, and it is an object to provide, an improved scrubber for aggregates such as sand and gravel whereby to remove dirt and foreign substance therefrom preparatory to commercial use of said aggregates.

Another object of the invention is to provide a scrubber, as above, which comprises a substantially horizontal rotary trommel fitted on the interior with novel means for elevating oversize aggregates and then dropping the same onto the slurry in the trommel so as to produce an effective pounding action on such slurry, which action materially facilitates the scrubbing of the aggregates in the machine.

A further object of the invention is to provide a scrubber, as in the preceding paragraph, in which said elevating means comprises a plurality of longitudinally extending, circumferentially spaced lifting grate units mounted in the trommel; each of said grates including a multiplicity of spaced, inwardly projecting fingers normally disposed in angled relation to the trommel axis in the direction of feed in the trommel.

An additional object of the invention is to incorporate, in the scrubber, a novel assembly for separating large and small aggregates, and for dewatering the larger aggregates before discharge thereof from the machine.

It is also an object to produce an aggregate scrubber which has a high capacity without sacrificing effective cleaning of the aggregates.

A further object of the invention is to produce a simple and inexpensive device, and yet one which will be exceedingly effective for the purpose for which it is designed.

These objects are accomplished by means of such structure and relative arrangement of parts as will fully appear by a perusal of the following specification and claims.

In the drawings similar character of reference indicate corresponding parts in the several views:

Figure 1 is a longitudinal sectional elevation, somewhat diagrammatic, of the machine.

Figure 2 is a cross section on line 2—2 of Fig. 1.

Figure 3 is an enlarged cross section on line 3—3 of Fig. 1.

Figure 4 is a fragmentary cross section on line 4—4 of Fig. 3.

Referring now more particularly to the characters of reference on the drawings, the machine comprises an elongated rotary body or trommel, indicated generally at 1; such trom-

2

mel being substantially horizontally and rotatably supported adjacent its ends by metallic rings or tires 2 which engage with pairs of transversely spaced trunnion rollers 3. The trommel 1 is driven in the direction of the arrow in Fig. 3, by any suitable means, shown in part at 4.

At the intake end 5 the trommel is formed with a central opening 6, through which a feed chute 7 projects at a forward and downward incline; said chute being adapted to feed aggregates and water into the trommel as a slurry.

Adjacent the intake end 5 of the trommel 1 the latter is fitted with a plurality of longitudinally extending, circumferentially spaced feeding vanes 8 projecting inwardly and pitched in a direction to cause the slurry to feed forwardly in the trommel. This section of the trommel is indicated generally at 9, while the trommel forwardly thereof is divided into other longitudinal sections, indicated generally at 10, 11 and 12.

The section 10, directly ahead of the initial or feeding section 9, is the scrubbing section and is constructed as follows:

25 Within the section 10 of the trommel 1 the same is fitted with a plurality of longitudinally extending, circumferentially spaced feeding vane units 13, each including a plurality of spaced, relatively short inwardly projecting vanes 30 pitched to cause continued advance of the slurry within the trommel, and particularly through said section 10. As shown, certain of the feeding vane units 13 are detachable from within the trommel. This permits removal of certain of 35 said units if it is desired to slow down the rate of feed of the slurry through the section 10.

Adjacent and alongside of the feeding vane units 13 the trommel is fitted with a corresponding number of longitudinally extending, circumferentially spaced lifting grate units 14, each of 40 which includes a multiplicity of spaced, inwardly projecting flat fingers 15 disposed edgewise to the direction of rotation of the trommel and in angled or pitched relation to the trommel axis, 45 and in the direction of feed through the trommel.

The angle of the fingers 15 is adjustable, as working conditions may require, by means of the following mounting thereof:

The fingers 15 are turnably supported, intermediate their ends, on cross pins 16, which in turn are attached at opposite ends to the trommel by bolts 17. The portions of the fingers 15, outwardly of the cross pins 16, extend into longitudinal, outwardly projecting housing 18 formed 55 on the trommel on the outside but opening to the

interior thereof. In each housing 18 there is a longitudinally extending slide block 19 formed with a plurality of equally spaced notches 20 in which rigid pins 21 on the fingers 15 engage; the pins projecting from the fingers 15 parallel to the cross pins 16. With sliding movement of the slide block 19 in a lengthwise direction the pin and slot assembly causes the fingers 15 to be adjusted in their angle relative to the axis of the trommel; said fingers normally being angled or pitched forwardly, i. e., in the direction of flow of slurry through the trommel.

The slide blocks 19 are mounted for such longitudinal sliding adjustment by means of opposed end trunnions 22 which are threaded and project through corresponding end walls 23 of the housings 18; adjustment nuts 24 being threaded on the trunnions 22 exteriorly of but in engagement with adjacent end walls 23. With adjustment of the nuts 24 in one direction or the other a corresponding adjustment of the slide block 19 is accomplished.

If desired, the fingers 15 may be set at right angles to the trommel, and metal balls or the like used as the grinding or crushing medium. These balls would be larger than the space between the fingers, and would remain in section 10. Only the crushed material, smaller than said spaces, would then be discharged from the section.

When the machine is in operation the slurry feeds from section 9 into section 10 and is advanced through the latter by the feeding vane units 13. As the trommel 1 rotates in the direction of the arrow in Fig. 3, the lifting grate units pick up oversized aggregates from the slurry and elevate such over-sized aggregates to a point adjacent but short of the top of the trommel. At such point the over-sized aggregates escape from said lifting grate units and fall downwardly onto the slurry, producing a grinding or pounding action, which materially facilitates the scrubbing of the material. As the fingers 15 of the lifting grate units 14 are angled or pitched in the direction of feed through the machine, the over-sized aggregates are progressively fed forwardly, while being recurrently raised and discharged to produce the above pounding action.

From the section 10 the slurry, including the over-sized aggregates, feeds over a radial baffle B onto a further section 11 which is perforate, and in the present embodiment comprises a multiplicity of longitudinally extending, circumferentially spaced bars 25 disposed in closely spaced relation, and which bars are circular in cross section. The section 11 also includes longitudinal rows of feeding vanes 26 in circumferentially spaced relation.

As the slurry feeds from section 10 into section 11 it is rinsed or flushed by water under relatively high pressure which discharges from one or more nozzles 27 within section 11. The nozzle is fed by a pipe 28 which enters the trommel axially from its forward or outlet end. Under the influence of the stream of water from the nozzle 27 the sand and smaller aggregates are flushed through the perforate section 11 of the scrubber into a bottom receiver 29 for further processing, as in a sand classifier or the like (not shown).

The oversized aggregates, i. e., those which cannot escape between the bars 25, are fed forwardly and, at the front end of the section 11, which may be termed the separating section, are picked up by a plurality of circumferentially spaced scoop plates 30 pitched in the direction of rotation of

the trommel. The scoop plates 30 project rearwardly from corresponding circumferentially spaced, longitudinally extending dewatering units 31, each of which units comprises a plurality of radial bars 32 disposed in spaced relation lengthwise of the trommel. The bars extend in fixed connection between an outwardly tapering cone 33 mounted in the section 12 in clearance relation to the outer wall thereof, and which outer wall tapers forwardly and inwardly at its end portion, as at 34. The taper of the end portion 34 of the section 12, which may be termed the dewatering section of the trommel, conforms substantially to the taper of the cone 33.

As the oversized aggregates are picked up by the scoop plates 30 from the section 11, such oversized aggregates are elevated on the dewatering units 31, the water draining from said over-sized aggregates as they are raised. As the dewatering units 31 approach the top of the trommel the oversized aggregates fall therefrom onto the cone 33 and thence discharge downwardly and outwardly into a hopper 35 for subsequent handling or processing.

The cone 33, at its forward end, includes a deflector plate 36 which prevents the oversized aggregates from spilling beyond the hopper 35, and assuring that such aggregates fall into said hopper.

From the foregoing description it will be readily seen that there has been produced such a device which substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. An aggregate processing machine comprising a driven, substantially longitudinally disposed rotary trommel; means to admit the aggregates into one end of the trommel in the form of a slurry, a plurality of longitudinally extending, circumferentially spaced, feeding vane units, mounted on the inner face of the trommel; each vane unit comprising a plurality of parallel, relatively short, radially projecting feeding vanes; said vanes being pitched with respect to the plane of rotation of the trommel to advance the slurry through the trommel; a longitudinally extending lifting grate unit immediately adjacent each feeding vane unit and in advance of the same in the direction of rotation; each grate unit comprising a plurality of parallel radially projecting fingers mounted on the inner face of the trommel, said fingers being of greater radial extension than the corresponding vanes, whereby as the trommel rotates the fingers will project into the moving slurry beyond the edges of the vanes and engage and lift the larger elements of the aggregates and then discharge them from adjacent the top of the trommel back into the slurry.

2. A machine as in claim 1 in which the fingers are pitched in the direction of movement of the slurry through the trommel.

3. An aggregate processing machine comprising a driven longitudinal trommel, and a plurality of longitudinally extending, circumferentially spaced lifting grate units mounted in the trommel, each unit including a row of spaced, inwardly projecting fingers, said fingers being flat and

disposed edgewise to the direction of rotation of the trommel and normally pitched in the direction of material flow therethrough, means pivotally mounting said fingers for adjustment of said pitch, and means connecting said fingers for adjustment thereof as a unit.

4. An aggregate processing machine comprising a driven longitudinal trommel, means forming a plurality of longitudinally extending, circumferentially spaced fingers projecting into the trommel from each of said pockets, cross pins on said fingers intermediate their ends turnably mounting the fingers on the trommel for adjustment of the pitch thereof lengthwise of said trommel, and means in each channel to which the fingers are connected for adjustment as a unit.

5. An aggregate processing machine comprising a driven longitudinal trommel, means forming a plurality of longitudinally extending, circumferentially spaced fingers projecting into the trommel from each of said pockets, cross pins on said fingers intermediate their ends turnably mounting the fingers on the trommel for adjustment of the pitch thereof lengthwise of said trommel, and means in each channel to which the fingers are connected for adjustment as a unit; said last named means comprising, for each row of fingers, a slide block in the channel, opposed end trunnions on the slide block extending through opposite end walls which define the ends of said pockets, and adjustment nuts threaded on said trunnions and engaging the outside of said end walls.

6. A machine as in claim 5 in which each slide block includes longitudinally spaced openings corresponding to the adjacent row of fingers, and actuating pins fixed on the fingers and projecting into corresponding openings; the actuating pins

being parallel to said cross pins, and the slide blocks being movable at a right angle thereto.

7. An aggregate processing machine comprising a longitudinal trommel having a perforate aggregate separating section, means to feed water into said section, a dewatering section beyond said separating section, said dewatering section including a plurality of circumferentially spaced, inwardly projecting perforate dewatering units operative to receive and elevate aggregates from the separating section for draining, means to feed aggregates from the separating section to the dewatering units, and catch means onto which said dewatering units discharge the drained aggregates; said aggregate feeding means comprising a scoop plate mounted on each dewatering unit and projecting into the adjacent end of said separating section, each scoop plate being pitched in the direction of rotation of the trommel.
